[57] **CLAIM**

The ornamental design for a turn lock cannula, as shown and described.

DESCRIPTION

FIG. 1 is a perspective view of a turn lock cannula, showing our new design;

FIG. 2 is a front elevational view thereof;

FIG. 3 is a back elevational view thereof;

FIG. 4 is a side elevational view thereof, the opposite side

elevational view being identical;

FIG. 5 is a top plan view thereof; and,

FIG. 6 is a bottom plan view thereof.
